UNITED STATES PATENT OFFICE

HUGH H. YOUNG, OF BALTIMORE, MARYLAND

AIRPLANE

Application filed January 30, 1931. Serial No. 512,430.

The present invention relates primarily to that class of airships commonly known as seaplanes or hydroplanes, and the primary object of the invention generally is the provision of novel and improved means for rendering such an airship stable and laterally steady when water-borne.

It is further among the objects of this invention to provide novel and improved means for minimizing any possible tendency of the airship to tip over onto its side when taking off or landing on water or land.

According to the instant invention, provision is made to effectively minimize or obviate rolling action of the seaplane when resting on the water and also any possible tendency to tip when making a landing, without involving the use of the commonly-employed fixed pontoons, which constitute a hindrance to the ship in flight because of their dead weight and resistance to air.

To this end, portions (intermediate or tip) of the wings of the seaplane are formed to constitute pontoons which are hingedly attached to the main body of the wings. Means is provided for the raising and lowering of these wing-portion pontoons, and for securely holding them in either position. In their raised position, they offer no resistance to flight comparable to that offered by ordinary pontoons, because they form, in effect, part of the wing structure. In smooth water, these pontoons are suspended from the wings above and adjacent to the surface of the water. Under a lateral rolling of the seaplane, such as would occur in rough water and as a result of which serious damage might result to the moored plane, the pontoons are alternately brought into contact with the water and tend to dampen the rolling motion of the vessel and to reduce it to a minimum.

To minimize a possible tipping of the plane when making a landing on the ground, the hingedly attached pontoons may preferably be provided with tire-rimmed ground-engaging wheels, adapted upon slight tipping of the ship to alternately come into contact with the ground, and stabilize the vessel.

The foregoing and other objects, which

to which the present invention pertains from a perusal of the detailed description below, are attained by the embodiments of the invention hereinafter disclosed, consisting of the construction and novel combination and arrangement of parts fully described below, illustrated in the accompanying sheets of drawings and pointed out in the claim hereunto appended.

In the drawings, 60

Fig. 1 represents a front elevational view of one form of airship with the present invention applied thereto; the pontoons being shown in lowered position in dotted lines;

Fig. 2 represents a side view of the airship 65 shown in Fig. 1;

Fig. 3 represents a front view of another form of airship with the present invention applied thereto;

Fig. 4 represents a side view of the plane 70 shown in Fig. 3;

Fig. 5 represents a view of an intermediate portion of the underside of one of the wings of the plane shown in Fig. 3;

Fig. 6 represents a side view of a portion 75 of a wing having a pontoon tip, a portion of the wing covering being omitted to illustrate the details of the pontoon raising-and-lowering means;

Fig. 7 represents a top plan view of Fig. 6; 80

Fig. 8 represents a view similar to Fig. 6, showing an intermediate portion of the wing utilized as the pontoon, the latter being shown in dotted lines in its raised position; and

Fig. 9 represents a top plan view of Fig. 8. 85

Similar reference numerals indicate similar or corresponding parts throughout the several views.

Referring now to the accompanying drawings, and more especially to Fig. 1 thereof, reference numeral 1 indicates the combined hull and fuselage of a conventional modern type of biplane amphibian, to which the present invention is adapted to be applied. The 90 said airship comprises also the engines 2 suitably mounted upon the hull, the propellers 3, and the usual navigating means 4. It will of course be understood that these several features of construction are merely 100

incidental to the present invention, and may therefore be varied at will.

Extending laterally from each side of the fuselage 1, and secured thereto in the usual manner, are the upper wings 5 and the lower wings 6. As the construction of each lower wing 6 is substantially the same, a description of one will suffice for both.

Each lower wing 6 comprises a conventional truss structure 7, of which only the rear spar and front spar are diagrammatically illustrated in the drawings (Figs. 6 and 8). This entire truss structure is preferably enclosed in a suitable covering or skin.

Each lower wing 6 is formed at its outer end with a separate wing tip portion 8 which is hingedly connected to the main body of the wing, as by hinges 9. These outermost portions 8 are formed of water-tight construction, and may preferably be made of riveted metal, plywood, or other equivalent material. The end of each lower wing proper 6 is provided with a water-tight wall 10. Due to their water-tight character, the wing tips 8 are adapted to act as pontoons, as hereinafter described.

When the airship is in flight, the wing tip pontoons 8 assume the horizontal position shown in full lines in Fig. 1, in which position they assume the function of and constitute portions or extensions of the wings proper 6. When the vessel is water-borne, the wing tip pontoons 8 are caused, by means of a suitable mechanism hereinafter described, to assume the vertical position illustrated in dotted lines in Figs. 1 and 2. In this latter position, they are adapted to effectively overcome and obviate any excessive tendency of the seaplane to roll laterally because of turbulent waters, and the ship is thus substantially stabilized.

Means is provided for simultaneously effecting the raising and lowering of the several wing tip portions 8. This means preferably comprises, for each wing pontoon, a pair of spaced bearings 11 and 12, which may be conveniently supported on one of the spars within the wing structure. Journaled in the said bearings 11 and 12 is the interiorly threaded shaft 13 which has a beveled gear 14 mounted on one end thereof.

Beveled gear 15, mounted upon rotatable shaft 16, meshes with the gear 14 of each wing-pontoon operating means, so that they may move simultaneously upon manual rotation of the shaft 16 by means of the hand-wheel control 17 thereon. It is obvious, of course, that suitable automatic means may be substituted for the hand-operated means. This means, whether manual or automatic, is so situated as to be conveniently accessible to the pilot, and rotation thereof effects rotation of the threaded shaft 13 in each wing 6.

Mounted for movement reciprocally of the interiorly-threaded shaft 13 upon rotation

of the latter is the exteriorly-threaded member 18, from which there extends a stainless steel operating tube or rod 19. Hingedly connected to the outer end of the rod 19 is one end of a lever 20, the other end of which is suitably and securely connected to the wing tip pontoon 8, as shown.

A lug 21 extends laterally from each lever 20 into guiding engagement with guides 22 mounted upon the spar member and acts to effectively limit the downward movement of the pontoons by the abutting of the lug 21 with ends or stops of the guides 22.

Thus a simple but efficient means is provided for simultaneously raising or lowering 80 the wing tip pontoons from the remote control in the cockpit of the airship.

It is preferred to form the outermost edges of the wing tip portions 8 of the contour shown in the drawings to enhance their effectiveness as pontoons, especially when the ship is moving through the water.

To enable the airplane to land on the ground, it is preferably provided with the specially-journalized single center wheel 23, which, if desired, may be made retractable while the plane is in flight. Each of the wing tip portions may also preferably be provided with a suitably journalized wheel, as shown at 24, care being taken to preserve the imperforate character of the covering of the pontoons 8. Means 23 and 24 constitute my novel and improved landing gear.

Upon landing on the ground, landing is made on the single center wheel 23, the plane being kept level by the usual controls until its speed has diminished. In the meantime, the portions 8 are lowered (as shown in dotted lines in Fig. 1) so that tipping of the plane, as it slows down, is prevented by one or the other of the wheels 24 coming into contact with the ground. The ground line is diagrammatically shown at 25 in Fig. 2, and the water line diagrammatically at 26.

In Fig. 3, the invention is shown as applied to a monoplane. In this form, an intermediate portion 8' of the wing 6' is hingedly movable with respect to the body of the wing. The portion 8' is functionally and constructionally similar to the pontoon 8 of the previously-described modification. It is obvious, of course, that wing tip pontoon may be used on the monoplane instead of the intermediate pontoons, and that intermediate pontoons may be used on the biplane instead of wing tip pontoons.

Means to raise and lower the pontoons 8' is shown in Figs. 8 and 9, and this means is substantially identical in structure and function with the corresponding means in the previously-described modification. The pontoons 8', however, are preferably hinged by suitable hinging means at the side thereof away from the cockpit instead of at the side nearest the cockpit, as in Figs. 6 and 7.

It is to be understood that the invention is susceptible of numerous slight changes within the scope of the appended claim. For example, in any of the modifications, the pontoons may be used with or without the wheels 24, or the center wheel may or may not be used in combination with the wheels 24. Similarly, the several wheels may be provided with suitable shock absorbers. Also, the several pontoons may be so arranged as to be individually and alternately, instead of simultaneously, raised and lowered. The disclosed modifications are merely exemplary or preferred embodiments of the present invention.

15 I claim:

15 Landing gear for airplanes of the character described including, in combination, a single center wheel, and combination stabilizing pontoons and balancer wheels depending from the wing extremities of the plane, and normally disposed above the level of said center wheel, said combinations stabilizing means being adapted to function as part of the wing when in flying position, said pontoons being watertight in character, and said balancer wheels being journaled in and extending from the pontoons, means for moving said combination stabilizing means, and means extending from said stabilizing means and coacting with said wing extremities for guiding and limiting the movement of the stabilizing means with respect to the plane, said guiding and limiting means comprising a lever connected to said stabilizing means, guides on said wing, and lug means on said lever adapted to abut with the ends of said guides.

HUGH H. YOUNG.
